BELL RINGING MECHANISM

William P. Wannemacher, Bloomington, Ill.

Application December 1, 1951, Serial No. 259,420

25 Claims. (Cl. 349—398)

This invention relates to a bell ringing device particularly applicable to ring the larger type of bells such as used in churches, courthouses and other public buildings.

The general practice has been to use one of two arrangements of mechanisms to ring bells of this character. One method is to employ mechanical means to rock a bell on its supporting trunnions, and the second method is to employ electrical means to actuate a striking member against the bell to ring the same. These two methods represent the chief means employed at the present time for ringing bells.

Both of these methods involve the use of complicated massive structures embodying expensive mechanisms. With the bell rocking systems, the mechanism is excessively massive, cumbersome and heavy, requiring the use of large heavy motors, and further necessitating special heavy wiring installation, all adding tremendously to the costs of such equipment. Installation and handling plus maintenance are all consonant high cost factors.

The electrical systems require large solenoids to actuate bell strikers and the latter normally range in weight from about twenty pounds to over one hundred pounds for the larger bells. Solenoids capable of handling such weights are very expensive and require large amperage current flow all necessitating special transformers and extra heavy wiring or bus bar equipment, all entirely out of line with the usual wire installations employed by code in buildings. Some cities will not permit such excessive intermittent use of amperage since that effects the current use in the lines in the surrounding neighborhood.

It has further been found that solenoid bell ringers do not produce true bell tones. For the best bell tone a striker of a given weight is required which must be actuated at a moderate rate of speed into contact with the bell.

One of the main objects of the present invention is to provide a bell ringer that simulates the moderate bell striking action of a clapper of a bell to produce a true clear bell tone ring.

Another object of the present invention is to provide a simple comparatively inexpensive mechanism that can be independently supported for operation within the bell cavity to ring the bell in clapper fashion.

A further object of this invention is to provide a mechanism that is comparatively light in weight, easily operated, and which can be operated on the normal building lighting circuit current and voltage.

Another object of the present invention is to provide a bell ringing mechanism that uses a striker that is for the greater part substantially gravity operated to thus minimize the use of and requirement for further energizing or mechanical means to carry out the bell ringing function of the striker.

A still further object of the present invention is to provide a gravitationally actuated striker that is cyclically controlled between given limits of operation to produce periodic clear ringing bell tones.

2

Other objects and advantages relating to the bell ringing mechanism of the present invention shall hereinafter appear in the following detailed description having reference to the accompanying drawings forming a part of this specification.

5 In the drawings:

Fig. 1 is a side elevational view of the bell ringing mechanism as supported and arranged within the bell cavity and adjacent one side of the bell for periodically ringing the latter;

10 Fig. 2 is a similar side elevational view to that illustrated in Fig. 1 but illustrating certain of the parts thereof in changed position;

Fig. 3 is an end elevational view of the bell ringing mechanism as seen from the left hand side of Fig. 1;

15 Fig. 4 is a plan view of the clapper or striker as it appears when removed from the balance of the mechanism;

Fig. 5 is a plan edge view of a weight that may be 20 added to the clapper or striker to change the total weight of the latter;

Fig. 6 is a detail cross sectional view taken vertically 25 through a portion of the bell ringing mechanism to illustrate certain details of construction thereof;

Fig. 7 is a view of the brake structure employed in the bell ringing mechanism to automatically lock all of the parts in a predetermined relationship after each ringing operation and prior to the next successive striker operation; and

30 Fig. 8 is a diagrammatic illustration of the electrical circuit employed to periodically cause the bell ringing mechanism to operate.

Referring to Fig. 1, the bell ringing mechanism is generally indicated at 1 for the purpose of striking a 35 peripheral edge of the bell 2, and this mechanism is supported upon a suitable frame structure comprising standards 3 and 4 connected with cross braces 5 and 6 which support a vertical panel 7 to which most of the operating parts are attached. The standards 3 and 4 of the frame 40 are suitably mounted upon the floor or any structural member such as 8 supported from the building and comprising a means for positioning the entire bell ringing mechanism within the bell cavity 9.

The bottom terminal edge portion 10 of the panel 7 45 is arcuately formed for cooperation with a guide or track 11 that is mounted on cross members 12 and 13 carried by the standards 3 and 4. A weight in the form of a clapper or striker 14 is movably supported between the terminal edge 10 and the track 11 and the latter form 50 guide means for the striker as the latter is moved therebetween. It should be noted that the both the curvature of the terminal edge 10 and the track 11 are substantially generated from the same point and that each of these guiding members terminate in high points 15 55 adjacent the bell and 16 radially inwardly from the bell edge.

As best seen in Figs. 1 and 4, the clapper 14 is provided with suitable pairs of wheels 17 and 18 with the latter riding upon the track 11 and with the former engaging the arcuate edge 10 of the panel 7 to maintain the clapper in a predetermined upright position between the guiding members. The head end 19 of the striker 14 is tapered and rounded as at 20 to provide a striking end which will not injure the bell but which will firmly 60 contact the latter to produce the bell ringing tone.

The striker 14 is also provided with a laterally supported roller 21 journaled upon a stub shaft 22, which roller 21 is flanked by a cam member 23 as best shown in Fig. 4.

65 The striker 14 is held in the position indicated in Fig. 1 by means of a latch bar 24 which is pivotally supported at 25 upon the panel 7. This latch bar 24

is arranged for engaging within a notch 26 that is formed into the upper surface of the clapper 14. The tail end 27 of the latch bar 24 is urged upwardly in a clockwise direction by means of a spring 28 carried upon a projection 29 secured to the panel 7. A suitable stop pin 30 may be employed to limit the turning motion of the latch bar in the clockwise direction and to normally position the latter for latching engagement with the striker 14.

The latch bar 24 normally remains in latched position until the end 27 thereof is engaged by the crank hub 31 which forms a portion of the worm gear 32 that is journaled upon a shaft 33 and which gear is driven by a worm 34 journaled in suitable bearings 35 and 36, all supported from the panel 7 and as best illustrated in Fig. 2.

The drive to the worm 34 is transmitted through a pulley drive as shown in Fig. 3 comprising a pulley 37 mounted upon the worm drive shaft 38 which connects with the worm 34, and rotation of the pulley 37 is instituted through the belt 39 carried by the pulley 40 which is mounted upon a shaft 41 of the motor 42. A magnetic brake arrangement such as illustrated in Figs. 2 and 7 is interposed between the pulley 37 and the worm 34 by connection with the shaft 38. This brake includes a brake wheel 43 fixedly connected to rotate with the shaft 38, which brake wheel is surrounded by a pair of brake shoes 44 and 45 that are pivoted at 46 and 47 upon a supporting member 48 that is connected with the panel 7. Both of the brake shoes include radial projections 49 and 50 which are normally pressed toward one another by means of the spring structure 51 and against a cam member 52 that is rotatably operated by means of a link 53 pivotally connected at 54 to a solenoid structure 55 that is vertically actuated by means of the solenoid 56 as best shown in Fig. 7.

This braking arrangement is normally active to hold the brake wheel 43 and shaft 38 in a fixed position and release of this braking arrangement is accomplished when the solenoid 56 is energized to cause the cam member 52 to rotate releasing the brake shoes 44 and 45 whereupon the drive from shaft 38 to the worm 34 may be freely transmitted.

An accelerating arm mechanism 57 comprises a means which is driven by the worm wheel 32 and which functions for engaging the clapper or striker to impart additional acceleration to such striker for the purpose of overcoming frictional retardation and to insure that the striker will return to its initial position at the forward high point 15 of the track guide members. This accelerator arm mechanism comprises an angle member 58 having one leg 59 disposed in a vertical plane and another leg 60 arranged at right angles to the leg 59, and this angle structure is pivotally carried at 61 upon a portion of the bearing structure 36 which is carried by the panel 7. A link 62 is pivotally connected with a pin 63 carried in the worm wheel boss 31 and this link 62 is also pivotally connected with the leg 59 of the angle member 58 upon a pin 64 carried by the latter.

The remaining structure of the accelerator arm 57 comprises a swingable arm 65 which is pivoted at 66 to the leg 60 of the angle member 58 and this arm 65 operates adjacent the extended portion of the leg 60 of the angle member 58. The extreme outer end of the arm 65 is provided with a cam follower 67 which is positioned and arranged for direct cooperation with a cam 68 that is carried upon a suitable supporting structure 69 also mounted upon the cross brace 12 of the frame structure. The accelerator arm construction 57 also includes a bracket 70 which is suitably slotted as at 71 to permit swinging of the arm 65 upon its pivot 66, and the bracket 70 carries a leaf spring 72 which is arranged to engage the edge of the arm 65 to normally maintain the same against the leg 59 of the angle structure 58 in the position best illustrated in Fig. 6.

The bell striking mechanism also includes a reactionary structure in the form of a leaf spring structure comprising a spring 73 that is secured to a bracket 74 carried upon the cross brace 5 with the free end 75 of the spring being disposed directly in the path of the striker 14 and adjacent the high point 16 of the guide trackway for the striker.

The operation of the bell ringing mechanism is best understood with reference to Fig. 1 which illustrates the 10 various cooperative mechanisms as they appear while in inoperative position. When current is supplied to the motor 42, the drive is transmitted to the worm 34 by means of the belt and pulley 39, 40 and 37, and the current supplied to the motor 42 is simultaneously arranged 15 for energizing the solenoid 56 to release the braking mechanism illustrated in Fig. 7. As the worm 34 is rotated, the worm wheel 32 begins to rotate in the direction of the arrow 76 which will cause the accelerating arm mechanism 57 to move from the full line position 20 shown in Fig. 1 toward the dotted line position illustrated therein. As the hub 31 on the worm wheel 32 is brought into the angular position illustrated in Fig. 2, the hub 31 will strike the end 27 of the latch bar 24 25 releasing the latch bar from the notch 26 in the striker 14, thus freeing the striker to permit the latter to roll down the incline of the arcuate supporting track comprising the members 10 and 11.

The striker 14 is therefore set into motion by gravity 30 from the high point to the right as illustrated in Figs. 1 and 2 whereby the striker would normally roll into the dotted line position as indicated at 77 in Fig. 1, from which position the gravitational tendency of the striker would be to return to its original position at the right of Fig. 1. However, due to frictional retardation, the striker 35 is somewhat slowed down and may not entirely come back to its original position. In the present device the striker is carried a slight distance from the interior surface of the bell as best shown in Figs. 1 and 2 so that a certain additional amount of movement is required to 40 bring the striker into full bell ringing contact with the interior of the bell, which means that an additional force will be necessary to actuate the striker over this additional distance. This also requires a slightly greater lift of the striker as the latter is propelled along the arcuate trackway.

The accelerator arm 57 provides the means for operating the additional impetus to fully overcome this frictional retardation and also to transmit additional energy to the moving striker 14 to firmly and properly hit the bell in a position beyond the normal latch position of the striker. 45 The accelerator arm 57 is so timed and arranged by means of the worm wheel link mechanism and the connecting link 62 as to be driven into the position illustrated in Fig. 2 immediately after the clapper 14 begins to roll to the left along its trackway. The arm 65 of the accelerator arm structure 57 will immediately catch up and engage the roller 21 on the clapper since the arm 65 travels slightly faster than the clapper in its travel along the trackway by reason of the link arrangement with the worm gear and the accelerator arm 57. With this action, the arm 65 causes the clapper or striker to accelerate along the trackway into the dotted line position 77 in Fig. 1 where the striker engages the reactionary spring 73 transmitting its stored energy into the spring. Immediately thereafter the spring 73 imparts impetus to the 50 striker 14 in the opposite direction causing the latter to move along the tracks 10 and 11 to the right to contact the bell for ringing the latter. Each of these reversals at either of the high points along the arcuate trackway is aided by the force of gravity acting upon the clapper or 55 striker 14 so that the invention includes a freely traveling weight which requires very little external power to provide a means for overcoming frictional retardation and also for introducing an additional impetus to the weighted clapper or striker for hitting the bell in the manner provided by the bell ringing mechanism.

In the operation of the accelerator arm structure 57, it should be noted that as the latter is moved to the right in Figs. 1 and 2, that the arm 65 engages the cam 23 which causes arm 65 to move outwardly of the clapper for clearing the roller 21, the spring 72 immediately restoring the arm 65 to its straight line position for engaging in back of the roller 21. This provides a swinging latch which will always properly engage the roller 21 in its movement to the right as shown in full lines in Fig. 2 and dotted lines in Fig. 1 for properly manipulating the weighted striker. Furthermore, at the other end of the stroke of the whipping accelerator arm the cam 68 is engaged by the follower 67 on the arm 65 which forces arm 65 outwardly and away from the plane of operation of the roller 21 so that this arm occupies the position best shown in Fig. 3 when the accelerator arm structure attains the position illustrated in full lines in Fig. 1. This particular arrangement and related positions of the parts is brought about immediately prior to the contact of the spring 73 by the striker 14 whereby the arm 65 is disposed out of the returning path of the clapper and roller 21 permitting free movement of the weighted striker 14 to ring the bell. This cycle of operation is repeated each time the bell is sounded.

It should also be understood that when a striker such as 14 here employed contacts the bell, the striker momentarily is stopped and does not rebound since the bell absorbs the shock. Therefore, after the bell is struck the striker merely returns by gravity to the full line position shown in Fig. 1 where it is again caught and latched by the latch bar 24 engaging within the slot 26 in the clapper.

This particular bell ringing mechanism may be employed for ringing a plurality of bells within a certain weight range by merely adding weights such as shown at 78 in Fig. 5. One or more weights such as 78 may be suitably bolted to the end 79 of the main weight or clapper 14 to attain a variation in the weight of the latter according to the size of the bells within the range for which this particular mechanism may be employed. It is also to be understood that the timing cycle may be changed by varying the size of the pulleys 37 and 40 and through the use of a belt appropriate for driving the pulleys.

To periodically and cyclically control the operation of the bell ringing function of the striker, the motor 42 may be energized in the manner best illustrated in Fig. 8. This circuit includes a transformer 80, a timing mechanism 81, a switch operating solenoid 82 and a mechanically controlled switch 83, together with the brake operating solenoid 56. The switch 83 is insulated and mounted upon a panel 84 and generally located as shown in Figs. 1 and 2. In this position the switch 83 is operated by means of the link 62 of the bell ringing mechanism. This link 62 when situated in the position illustrated in Fig. 1 is in contact with a cam clip 85 as shown in Fig. 8 and when the parts are in the relationship illustrated, the switch contacts 86 and 87 are open and separated at the ends of the resilient spring elements 88 and 89 respectively. Switch 83 closes immediately upon movement of the link 62 in the direction of the arrow 90 which is also the direction of rotation of the worm wheel 32. The motor 42 is energized by means of the timing mechanism 81 which includes a time clock 91 arranged to drive the timing wheel 92 which is notched as at 93 to receive the projection 94 of the contact lever 95 within such notches. The lever 95 is pivoted at 96 and is provided with a contact 97 for engagement with an adjustable contact 98 whenever the projection 94 drops into one of the notches 93.

When the time clock 91 rotates the timing wheel 92 in the direction of the arrow indicated in Fig. 8, projection 94 will drop into a notch 93 completing the circuit through the contacts 97 and 98 as follows. Current is taken from the 110 volt lines 99 and 100 by means

of a lead 101 to the transformer 80 which reduces the 110 volt house current to a 24 volt circuit current for operating the incidental devices used in controlling the circuit to the motor 42. The positive transformer current from the line 101 is continued through the line 102 for connection with the terminal 98 of the timing switch. When arm 95 is dropped to complete the circuit through the contact 97 the current flows through the leads 103 and 104 to energize the switch operating solenoid 82 closing the solenoid switch 83' with the solenoid current returning through lead 105 back through the transformer 80 and line 106 to the negative side 100 of the house current. As the switch 83' is closed, an independent circuit is established to operate the motor 42 and to energize the solenoid and brake mechanism 56 releasing the brake and permitting the motor drive to be transmitted to the bell operating mechanism. This motor circuit comprises a line 107 leading from the positive side 99 of the house current to the motor through the line 108 with the line 109 returning through switch 83' and through lead 110 to the negative side 100 of the house line. A parallel circuit is established by means of the leads 111 and 112 to operate the brake solenoid 56.

The moment the switch 83' is closed by the timing mechanism, the worm 34 rotates the worm wheel 32 which immediately moves link 62 in the direction of the arrow 90 as illustrated in Fig. 8. At this instant, the cam clip 85 is freed from the end 113 of the link 62 permitting the contacts 86 and 87 to close, thereby establishing an auxiliary circuit to hold the solenoid switch 83' closed after the timing mechanism again operates the contacts 97 and 98. This new circuit establishes a flow of current through the line 114 from the positive side 99 of the house line through the switch 83' back through the line 115 and through the lead 104 through the switch operating solenoid 82. This circuit is then completed as before through the line 105 through the transformer 80 and line 106 back to the negative side of the house current.

When this condition exists, the motor 42 continues to operate until the link 62 has completed its cycle of operation for actuating the accelerating arm 57 at which time link 62 again comes into the position shown in Fig. 8. When this occurs, the cam clip 85 is again actuated to open the contacts 86 and 87 whereupon the solenoid switch 83' is opened since the switch operating solenoid 82 is immediately deenergized and this brings about the immediate interruption of the house current to the motor 42 and brake solenoid 56. Overrunning of the motor drive to the worm 34 is, therefore, instantly stopped by the brake structure illustrated in Fig. 7 after the solenoid 56 is deenergized.

This cyclic operation can be repeated according to the particular type of timing wheel used at 92 as controlled by the time clock 91.

The foregoing description is directed to a preferred embodiment of the bell ringing mechanism of the present invention. It is to be understood, however, that certain changes and modifications are contemplated which will not depart from the general concept of this invention. Such changes and modifications shall be governed by the breadth and scope of the appended claims directed to this invention.

What I claim is:

1. A bell ringing mechanism comprising a support, a striker, and arcuate guides on said support having spaced elevated portions thereon, said striker being carried for reciprocable movement upon said guides and arranged for gravitational operation to and fro therealong and between said spaced elevated portions of said guides, and said support comprising means to position said guides in predetermined relation with respect to a bell whereby the bell is contacted by said striker.

2. A bell ringing mechanism comprising a support, a striker, and arcuate guides on said support, said striker

being carried for reciprocable movement upon said guides and arranged for gravitational operation to and fro therealong, and said support comprising means to position said guides in predetermined relation with respect to a bell whereby the bell is contacted by said striker during one direction of movement of the striker, and operative means including a swingably supported member constructed and arranged for abuttingly coacting with said striker to control the motion of the striker relative to said guides while said striker moves in said one direction.

3. A bell ringing mechanism comprising a support, a striker, and arcuate guides on said support having spaced elevated portions thereof, said striker being carried for reciprocable movement upon said guides and arranged for gravitational operation to and fro therealong and between said spaced elevated portions of said guides, and said support comprising means to position said guides in predetermined relation with respect to a bell whereby the bell is contacted by said striker, and periodically operable mechanism cooperating with said striker to cyclically control the striker for the bell ringing operation.

4. A bell ringing mechanism comprising a support, a striker, and arcuate guides on said support, said striker being freely carried for back and forth movement upon said guides and arranged for gravitational operation therealong, and said support comprising means to position said guides in predetermined relation with respect to a bell whereby the bell is contacted by said striker, and striker accelerating mechanism including an operable striker engaging member constructed and arranged for intermittent striker contact and to impart impetus to said striker while the latter is in motion and during one direction of movement of the striker along said arcuate guides.

5. A bell ringing mechanism comprising a support, a striker, and arcuate guides carried upon said support and constructed and arranged to provide at least two elevated positions thereon, said striker being carried for back and forth movement upon said guides and arranged for gravitational operation therealong and between said two elevated positions on said guides, and said support comprising means to position said guides in predetermined relation with respect to a bell whereby the bell is contacted by said striker, and striker accelerating mechanism including an operable striker engaging member to impart impetus to said striker and at least during one direction of movement of the striker along said arcuate guides, and releasable latch means to retain said striker in one of said two elevated positions upon said arcuate guides.

6. A bell ringing mechanism comprising a support, a striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during one direction of movement of the striker along said arcuate guides, and releasable latch means to position said striker in a predetermined inoperative raised location upon said arcuate guides, and power driven mechanism connected to actuate said striker accelerating mechanism and including means to release said latch means at predetermined cyclic periods.

7. A bell ringing mechanism comprising a support, a striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during

one direction of movement of the striker along said arcuate guides and releasable latch means to position said striker in a predetermined inoperative raised location upon said arcuate guides, and power driven mechanism connected to actuate said striker accelerating mechanism and including means to release said latch means at predetermined cyclic periods, and time control means connected with said power driven mechanism to periodically institute a striker cycle of operation to ring the bell.

10. 8. A bell ringing mechanism comprising a support, a striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during one direction of movement of the striker along said arcuate guides, and releasable latch means to position said striker in a predetermined inoperative raised location upon said arcuate guides, and power driven mechanism connected to actuate said striker accelerating mechanism and including means to release said latch means at predetermined cyclic periods, and time control means connected with said power driven mechanism to periodically institute a striker cycle of operation to ring the bell, said time control means having a positive timing element connected therewith to operate associated means controlling said power driven mechanism whereby periodic bell ringing combinations are obtainable.

9. A bell ringing mechanism comprising a support, a striker, and arcuate guides on said support arranged concavely upwardly and for disposition with one raised end of said guides adjacent one side portion of a bell and with the other raised end of said guides located away from said side portion of the bell, said striker being carried for movement upon said guides and arranged for gravitational operation therealong, and said support comprising means to position said guides in predetermined relation with respect to said side portion of said bell whereby the bell is contacted by said striker, and striker accelerating mechanism including an operable striker engaging member to impart impetus to said striker and at least during one direction of movement of the striker along said arcuate guides, and releasable latch means to position said striker in a predetermined inoperative raised location upon said arcuate guides, and rebound means for said striker, said latch means being positioned adjacent one raised end of said arcuate guides, and said rebound means being positioned adjacent the other raised end of said guides.

10. A bell ringing mechanism comprising a support, a striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during one direction of movement of the striker along said arcuate guides, and releasable latch means connected with said striker to position said striker in a predetermined inoperative raised location upon said arcuate guides, and rebound means for said striker, said latch means being positioned adjacent one end of said arcuate guides, and said rebound means being positioned adjacent the other end of said guides, and striker accelerating mechanism arranged for limited contact with said striker upon release of the striker by said latch means, said accelerating mechanism imparting additional impetus to the gravitationally operated striker and in the direction of said rebound means.

11. A bell ringing mechanism comprising a support, a

striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during one direction of movement of the striker along said arcuate guides, and releasable latch means to position said striker in a predetermined inoperative raised location upon said arcuate guides, and rebound means for said striker, said latch means being positioned adjacent one end of said arcuate guides, and said rebound means being positioned adjacent the other end of said guides, and striker accelerating mechanism arranged for limited contact with said striker upon release of the striker by said latch means, said accelerating mechanism imparting additional impetus to the gravitationally operated striker and in the direction of said rebound means, and cooperative means carried by said striker accelerating mechanism and said striker whereby said latter mechanism and striker are operatively connected and disconnected between predetermined limits of motion of said striker along said arcuate guides.

12. A bell ringing mechanism comprising a support, a striker, and arcuate guides on said support, said striker being carried for movement upon said guides and arranged for gravitational operation therealong, and said support comprising means to position said guides in predetermined relation with respect to a bell whereby the latter is contacted by said striker, and striker accelerating mechanism including an operable striker engaging member to impart impetus to said striker and at least during one direction of movement of the striker along said arcuate guides, and releasable latch means to position said striker in a predetermined inoperative raised location upon said arcuate guides, and rebound means for said striker, said latch means being positioned adjacent one end of said arcuate guides, and said rebound means being positioned adjacent the other end of said guides, and striker accelerating mechanism arranged for limited contact with said striker upon release of the striker by said latch means, said accelerating mechanism imparting additional impetus to the gravitationally operated striker and in the direction of said rebound means, and cooperative means carried by said striker accelerating mechanism and said striker whereby said latter mechanism and striker are operatively connected and disconnected between predetermined limits of motion of said striker along said arcuate guides, said cooperative means comprising an arm supported to bodily swing adjacent the plane of the arcuate guides, an abutment unit on said striker for engagement by said arm, said abutment unit and arm being disposed in the same plane of operation, said arm being arranged to swing laterally out of said plane of operation, and cam means carried by said striker and by said support to actuate said arm laterally outwardly whereby the arm may swing in one direction to engage behind the striker abutment unit and be released therefrom as said arm swings in another direction.

13. A bell ringing mechanism comprising an arcuate guideway curving concavely upwardly, a bell striking member supported for gravitational movement along said guideway, releasable detent means coacting with said member to hold the same at a predetermined elevation upon one portion of said guideway, and operative mechanism to release said detent means to free said member for gravitational motion along said guideway through the lowermost portion thereof and toward another elevated portion of said guideway disposed substantially at the elevation of said starting point, whereby said member reverses for gravitational motion toward the starting point, said guideway being positioned with said starting

point adjacent a bell to direct said bell striking member thereagainst.

14. A bell ringing mechanism comprising a framework supported adjacent a side of a bell, an upwardly curved guideway on said framework, said guideway terminating with elevated ends and with one end of said guideway positioned in a given relation to the side of the bell, and a striker movably supported upon said guideway for to and fro gravitational operation between said elevated ends on said upwardly curved guideway, one of said guideway ends being disposed adjacent said bell whereby the bell is contacted by said striker each time the striker reaches said one guideway end.

15. A bell ringing mechanism comprising a framework supported adjacent a side of a bell, an upwardly curved guideway on said framework positioned in a given relation to the side of the bell, and a striker movably supported upon said guideway for gravitational operation between two high points on said guideway, one of said high points being adjacent said bell whereby the bell is contacted by said striker each time the striker reaches said one high point, power operated mechanism to periodically regulate the movements of said striker in its travel between said high points on said guideway, and automatic brake means connected with said power operated mechanism and arranged to interrupt the bell ringing cycle of the associated moving parts of said mechanism at a predetermined period for each subsequent cyclic operation of such parts.

16. A mechanism for ringing a bell comprising an inclined guideway supported to terminate adjacent one wall of a bell, said guideway having a high point thereon located adjacent said bell wall, a weight mounted upon said guideway for gravitational movement therealong, latch mechanism to retain said weight at said high point and in predetermined relation with respect to said bell wall, control means to release said latch mechanism to free said weight for gravitational movement down said inclined guideway and away from said bell wall, rebound means disposed in predetermined relation with respect to said guideway and away from said bell wall and in position to be engaged by said weight, and accelerating mechanism arranged to coact with said weight and to impart increased momentum to the weight upon release of the latter in the direction of said rebound means and to cause said weight to strike said rebound means whereby the motion of said weight is reversed and said weight is propelled upwardly along said inclined guideway to strike said bell wall.

17. A mechanism for ringing a bell comprising an inclined guideway supported to terminate adjacent one wall of a bell, said guideway having a high point thereon located adjacent said bell wall, a weight mounted upon said guideway for gravitational movement therealong, latch mechanism to retain said weight at said high point and in predetermined relation with respect to said bell wall, control means to release said latch mechanism to free said weight for gravitational movement down said inclined guideway and away from said bell wall, rebound means disposed in predetermined relation with respect to said guideway and away from said bell wall and in position to be engaged by said weight, and accelerating mechanism arranged to coact with said weight and to impart increased momentum to the weight upon release of the latter in the direction of said rebound means and to cause said weight to strike said rebound means whereby the motion of said weight is reversed and said weight is propelled upwardly along said inclined guideway to strike said bell wall, said accelerating mechanism comprising a swingably operated member arranged for bodily contact with said weight and for a limited portion of the gravitational movement of the weight in its travel between said latch mechanism and said rebound means.

18. A mechanism for ringing a bell comprising an inclined guideway supported to terminate adjacent one wall

of a bell, said guideway having a high point thereon located adjacent said bell wall, a weight mounted upon said guideway for gravitational movement therealong, latch mechanism to retain said weight at said high point and in predetermined relation with respect to said bell wall, control means to release said latch mechanism to free said weight for gravitational movement down said inclined guideway and away from said bell wall, rebound means disposed in predetermined relation with respect to said guideway and away from said bell wall and in position to be engaged by said weight, and accelerating mechanism arranged to coact with said weight and to impart increased momentum to the weight upon release of the latter in the direction of said rebound means and to cause said weight to strike said rebound means whereby the motion of said weight is reversed and said weight is propelled upwardly along said inclined guideway to strike said bell wall, said accelerating mechanism comprising a swingable arm mounted for movement along the path of operation of said weight, an abutment member on said weight disposed in the path of said arm, and driving means to swing said arm to and fro along said weight path and to bodily actuate said weight along said guideway away from said bell wall, said arm including releasable means thereon arranged for disengagement from said abutment member at one point along the path of travel of said weight, and said releasable means being constructed and arranged to reengage said abutment member on said weight at another point along the path of travel of said weight.

19. A mechanism for ringing a bell comprising an inclined guideway supported to terminate adjacent one wall of a bell, said guideway having a high point thereon located adjacent said bell wall, a weight mounted upon said guideway for gravitational movement therealong, latch mechanism to retain said weight at said high point and in predetermined relation with respect to said bell wall, control means to release said latch mechanism to free said weight for gravitational movement down said inclined guideway and away from said bell wall, rebound means disposed in predetermined relation with respect to said guideway and away from said bell wall and in position to be engaged by said weight, and accelerating mechanism arranged to coact with said weight and to impart increased momentum to the weight upon release of the latter in the direction of said rebound means and to cause said weight to strike said rebound means whereby the motion of said weight is reversed and said weight is propelled upwardly along said inclined guideway to strike said bell wall, said accelerating mechanism comprising a member movable along the path of motion of said weight, and variable drive means connected with said member and arranged to actuate the latter at an accelerated rate of speed ranging at least from the normal gravitationally induced starting speed of said weight to a rate of speed greater than the normal accelerated rate of motion of said weight along said guideway.

20. A mechanism for ringing a bell comprising an inclined guideway supported to terminate adjacent one wall of a bell, said guideway having a high point thereon located adjacent said bell wall, a weight mounted upon said guideway for gravitational movement therealong, latch mechanism to retain said weight at said high point and in predetermined relation with respect to said bell wall, control means to release said latch mechanism to free said weight for gravitational movement down said inclined guideway and away from said bell wall, rebound means disposed in predetermined relation with respect to said guideway and away from said bell wall and in position to be engaged by said weight, and accelerating mechanism arranged to coact with said weight and to impart increased momentum to the weight upon release of the latter in the direction of said rebound means and to cause said weight to strike said rebound means whereby the motion of said weight is reversed and said weight is

propelled upwardly along said inclined guideway to strike said bell wall, said accelerating mechanism comprising a member movable along the path of motion of said weight, and variable drive means connected with said member and arranged to actuate the latter at an accelerated rate of speed ranging at least from the normal gravitationally induced starting speed of said weight to a rate of speed greater than the normal accelerated rate of motion of said weight along said guideway, said movable member comprising a swingably mounted arm, and said variable drive means including crank and link means connected with said movable arm.

21. A mechanism to ring a bell comprising a trackway having upwardly inclined ends with one end thereof supported adjacent one wall portion of a bell, a weighted bell striker, retention mechanism to normally hold said striker in an elevated position at one end of said trackway for gravitational movement to and fro upon and along said trackway, said bell being contacted by said striker in its to and fro motion over said trackway, and supplementary weight sections for attachment to said striker to provide means to increase the total overall weight of said striker and to accelerate the to and fro travel of said striker over said trackway to build up the impact energy of said striker in proportion to the mass and size of the bell associated therewith.

22. A mechanism to ring a bell comprising a guideway supported in a given relation with respect to one portion of the wall of a bell, a striker of a given weight mounted for movement upon and along said guideway, cooperative mechanisms coacting with said striker to control the movement of said striker in back and forth relation upon the guideway and to cause said striker to engage said bell wall during at least one direction of motion thereof, and cooperative separable parts including weight sections arranged for securing to said striker to increase the total operative weight of said striker according to the mass and size of the associated bell therewith, and coacting mechanisms connected with said striker to control and limit the travel of said striker along said trackway, one of said mechanisms comprising a latch unit to retain said striker at one location along said guideway, and the other mechanism comprising a resilient rebound unit at another location along said guideway.

23. A mechanism to ring a bell comprising a trackway having upwardly inclined ends with one end thereof supported adjacent one wall portion of a bell, a bell striker comprising a weight, and wheeled means thereon engaging said trackway to guide the weight in a given and oriented relation along said trackway, said weight being arranged and supported for back and forth gravitational motion over said trackway whereby to intermittently strike and ring said bell, and impetus mechanism comprising a movable element arranged for actuation in a given path with respect to said weight, and an abutment on said weight engageable by said element, said wheeled means and trackway functioning to maintain said weight and its abutment in operable relation with respect to said movable element during the motion of said weight over said trackway.

24. A mechanism to ring a bell comprising a trackway having upwardly inclined ends with one end thereof supported adjacent one wall portion of a bell, a bell striker comprising a weight, and wheeled means thereon engaging said trackway to guide the weight along said trackway and in a predetermined oriented relation with respect to said trackway, said weight being arranged and supported for back and forth gravitational motion over said trackway whereby to intermittently strike and ring said bell, and coacting mechanisms connected with said striker to control and limit the travel of said striker along said trackway comprising a latching unit to engage a given portion of said striker, and a rebound unit, both of said units occupying predetermined positions with respect to said trackway, and said wheel means functioning to main-

tain said coacting mechanisms and said striker in their respective cooperative working relationships.

25. A mechanism to ring a bell comprising a trackway having upwardly inclined ends with one end thereof supported adjacent one wall portion of a bell, a bell striker comprising a weight, and wheeled means thereon engaging said trackway to guide the weight along said trackway, said weight being arranged and freely supported for back and forth gravitational motion over said trackway and from one to the other of said inclined ends thereof whereby to intermittently strike and ring said bell, said trackway including at least one weight supporting rail, and said wheeled means having operative

5

rolling connection with said rail to carry the striker therealong to continuously engage said bell in a given oriented and predetermined relation.
